[57] CLAIM

The ornamental design for a container cover, as shown and described.

DESCRIPTION

FIG. 1 is a perspective view of a container cover according to my design;

FIG. 2 is a top plan view thereof;

FIG. 3 is a bottom plan view thereof;

FIG. 4 is a right side elevational view thereof;

FIG. 5 is a left side elevational view thereof; and,

FIG. 6 is a front elevational view thereof, the rear elevational view being identical to the front elevational view;

The broken line illustration in the drawing disclosure is not part of the design sought to be patented.
